UNITED STATES PATENT OFFICE.

WILLIAM TOWERS, OF MURPHYSBORO, ILLINOIS.

CAGE FOR MINING-CARS.

SPECIFICATION forming part of Letters Patent No. 714,262, dated November 25, 1902.

Application filed June 2, 1902. Serial No. 109,988. (No model.)

To all whom it may concern:

Be it known that I, WILLIAM TOWERS, a citizen of the United States, residing at Murphysboro, in the county of Jackson, State of Illinois, have invented certain new and useful Improvements in Cages for Mining-Cars, of which the following is a specification, reference being had therein to the accompanying drawings.

This invention relates to a cage for mining-cars, and more particularly to a construction wherein a descending elevator automatically operates means for releasing a loaded car from a receiving-platform, so that the same may contact with and remove an empty car from the elevator.

The invention has for an object to provide a novel construction of pivoted platform which is inclined in the descending movement of the elevator and provided with an automatically-operated retaining-dog, which is released as the platform is inclined, so that the car upon the platform rolls forward upon the elevator, pushing the car previously on the elevator therefrom.

A further object of the invention is to provide an improved construction of automatically-operated dog for engaging the wheels of the car upon the elevator, which dog is automatically released as the elevator descends into alinement with an adjacent track, so as to permit the removal of the car upon the elevator while the dog is again engaged with the wheels of another car after the passage of the unloaded car from the elevator.

A further object of the invention is to provide a novel construction of dogs for the retaining and caging operations, so arranged as to be automatically operated to accomplish the purpose of this invention.

Other and further objects and advantages of the invention will be hereinafter set forth, and the novel features thereof defined by the appended claims.

In the drawings, Figure 1 is an elevation illustrating in dotted lines the operation of the elevator-cage and adjacent parts. Fig. 2 is a detail elevation of the operating connections between the elevator, pivoted platform, and retaining-dog. Fig. 3 is a vertical section on the line 3-3 of Fig. 2. Fig. 4 is a sectional elevation of the elevator-cage, caging-

dog thereon, and trip mechanism coöperating with said dog. Fig. 5 is a vertical section on the line 5-5 of Fig. 4. Fig. 6 is a similar view of the dash-pot used in connection with this invention, and Fig. 7 a detail of one of the caging-dogs upon the elevator.

Like letters of reference refer to like parts in the several figures of the drawings.

The letter A indicates an elevator-cage of any suitable construction supported and operated by a cable connection A' and provided at its lower portion with a platform A², having suitable tracks C³ thereon, adapted to receive the bearing-wheels of a mining-car A³, of any desired construction. At one side of this elevator-cage a receiving-platform B is pivotally mounted—for instance, upon a foundation B'—by means of a bearing B² and is provided upon its upper surface with tracks or rails C, in alinement with those upon the elevator-cage. The end B³ of this platform is of greater weight than the end B⁴, so that the platform is normally retained in a horizontal position, as shown by full lines in Fig. 1, with the end B³ resting upon a suitable support B⁵, so that the rails C thereof are in alinement with similar rails C' upon an adjacent surface. At the opposite side of the elevator tracks or rails C² are arranged upon a surface in a lower plane than the rails C' and adapted to be in alinement with the rails C³ upon the elevator-cage when the latter is lowered to its position of rest upon the support C⁴.

For the purpose of tilting one end of the pivoted receiving-platform B, which is adapted to receive a loaded car A³, a projecting plate D is secured to the end B⁴ of the platform and extends beneath the elevator-platform A², so as to be carried downward thereby, thus inclining the parts into the position shown in dotted lines in Fig. 1 when the elevator has reached its point of rest. In order to release the loaded car held upon the loaded elevator at this time, the retaining-dog E therefor must be actuated to withdraw it from contact with the wheels of the car, and for this purpose a link D' is pivotally connected to the free end of the plate D and to one end of a lever D², mounted upon a fixed support D³, the opposite end of which is pivotally connected to toggle-levers D⁴, as shown in Fig.

3. The ends of these toggles are similarly pivoted to the depending lever ends E', extending downward below pivots E² of the retaining-dogs E, which dogs are provided with 5 an inwardly - deflected curved portion E³, forming a shoe to engage the periphery of the wheel upon the car. It will thus be seen that a downward movement of the plate D causes an upward movement of the inner end of the 10 lever D², thus throwing the toggle-levers D⁴ into the position shown by dotted lines in Fig. 3, and removes the shoes E³ of the dogs from the wheels, so that the incline of the platform carries the car by gravity into contact with the car upon the elevator, which 15 has at this time been released by means to be hereinafter described.

For the purpose of preventing a sudden movement of the platform B into an inclined 20 position a dash-pot F is provided, as shown in detail by Fig. 6, the cylinder of which is filled with oil or any suitable liquid, and the piston-rod F' thereof is provided with the usual packed piston F², having a small aperture therethrough. The free end of the piston-rod is pivotally secured to the end of the platform, and the by-pass F³ extends from one end of the cylinder to the other and is provided with a check-valve F⁴ opening inwardly toward the cylinder. It will thus be seen that in the downward movement of the piston the liquid gradually passes through the small opening in the piston and permits an easy downward movement of the platform 30 upon which the loaded weight of a loaded car is usually supported, while the by-pass permits a quick return of the platform to a horizontal position as soon as the elevator-cage is removed from contact therewith. It will be 35 observed that an interlocking joint is formed between the tracks C and C³ at their meeting end, so that no break or obstruction is formed when the parts are in an inclined position which would be liable to cause a derailment 40 of the car.

For the purpose of securely retaining a car A³ upon the elevator-platform caging-dogs G are provided, which embrace one or both of the wheels and are pivotally mounted at G', 50 while the lower lever ends G² thereof are connected by rods G³ with crank-arms G⁴, carried by the shaft G⁵, extending longitudinally beneath the platform A². This shaft also carries a weighted arm G⁶ for automatically throwing and holding the dogs G in contact with the car-wheels, and the said dogs are released, as shown by dotted lines 55 in Fig. 5, by an upward movement of this weighted arm. For the purpose of producing this upward movement any desired means 60 may be used; but a trip-block H is here shown, which in the position shown by full lines in Fig. 4 engages and raises the weighted arm G⁶ to release the dogs from the 65 wheels and permit the car to be moved from the cage into the position shown by dotted lines. This trip-block is provided with a

seat H' below the plane of the upper face of the block, and the inner end thereof is pivotally connected at H² to a lever H³, which 70 is normally held in its full-line position by means of a weight H⁴, assisted, if necessary, by a spring H⁵. As the car passes over this lever the same is depressed by contact with the car into the position shown in dotted 75 lines, withdrawing the trip-block H, so that the seat H' lies beneath the weighted arm G⁶, which in its movement downward to this seat throws the caging-dog into engagement with the wheels of the car which has now 80 passed from the platform B onto the elevator-cage. The parts are now in position to raise the elevator and car thereon, while another loaded car is moved upon the platform for automatic operation in the return of the 85 elevator. In the event that the caging-dog G is not thrown fully out of the plane of the approaching wheels of the car from the platform an inclined end portion G⁷ is provided, which by contact with the wheels throws the 90 dog laterally and permits the car to pass into proper position to be caged on the elevator.

The operation of the several parts of the invention will be apparent from the foregoing description, and it will be noted that 95 when the parts are in the position shown by full lines in Fig. 1 a further downward movement of the elevator-cage will tilt the platform and automatically release the dogs upon the platform and the elevator, so that 100 the car from the platform moves forward by gravity, pushing the car off the elevator and taking its place thereon. The car leaving the elevator immediately operates the trip-block through its lever, permitting the caging-dog to at once engage and hold the car in 105 a proper position upon the elevator. It will thus be seen that the loading and unloading of the car is entirely automatic, and the only labor required is the placing of the car upon 110 the platform and the removal of the car after it has left the elevator, thus preventing 115 all danger of accidents and injury to employees in handling cars upon elevator-cages which may be in movement at the time. It 120 will also be seen that the automatic operation of the dogs are capable of application in other connections than the particular relation of parts here shown, as the automatic operation is capable of use in connection 125 with any form of apparatus.

It will be obvious that changes may be made in the details of construction and configuration of the invention without departing from the spirit thereof as defined by the appended 130 claims.

Having described my invention and set forth its merits, what I claim, and desire to secure by Letters Patent, is—

1. In a device of the class described, an elevator, caging means for securing a car thereon, a platform at one side of said elevator, a retaining means for a car upon said platform, connections to be engaged by said elevator 135

- for automatically releasing said retaining means and caging means; and means actuated by the car leaving the platform to reengage the caging means with a following car; 5 substantially as specified.
2. In a device of the class described, an elevator, caging means for securing a car thereon, a platform at one side of said elevator, a retaining means for a car upon said platform, 10 connections to be engaged by said elevator for automatically releasing said retaining means and caging means, and means for tilting said platform toward said elevator in the downward movement of the latter; substantially as specified. 15
3. In a device of the class described, an elevator, caging means for securing a car thereon, a platform at one side of said elevator, a retaining means for a car upon said platform, 20 connections to be engaged by said elevator for automatically releasing said retaining means and caging means, means for tilting said platform toward said elevator in the downward movement of the latter, and means 25 for permitting the reengagement of the caging device upon the elevator after the latter has reached the downward limit of its movement; substantially as specified.
4. In a device of the class described, an elevator, caging means for securing a car thereon, a platform at one side of said elevator, a retaining means for a car upon said platform, 30 connections to be engaged by said elevator for automatically releasing said retaining means and caging means, means for tilting said platform toward said elevator in the downward movement of the latter, means for 35 permitting the reengagement of the caging device upon the elevator after the latter has reached the downward limit of its movement, and means beneath the descending end of 40 said platform for restraining the movement thereof; substantially as specified.
5. In a device of the class described, an elevator, caging means for securing a car thereon, a platform at one side of said elevator, a retaining means for a car upon said platform, 45 connections to be engaged by said elevator for automatically releasing said retaining means and caging means, means for tilting said platform toward said elevator in the downward movement of the latter, means for 50 permitting the reengagement of the caging device upon the elevator after the latter has reached the downward limit of its movement, and means beneath the descending end of 55 said platform for restraining the movement thereof, and a trip-lever operated by a car for actuating said reengaging means; substantially 60 as specified.
6. In a device of the class described, an elevator-platform, a pivoted platform at one side thereof having a projection to engage beneath said elevator, car-retaining means upon said 65 pivoted platform automatically operated by the tilting thereof, and means for restoring said platform to its initial position when the
- elevator-platform is out of engagement therewith; substantially as specified.
7. In a device of the class described, an elevator-platform, a pivoted platform at one side thereof having a projection to engage beneath said elevator, means for restoring said platform to its initial position when the elevator-platform is out of engagement therewith, and 70 a pivoted retaining-dog carried by said pivoted platform and movable away from the wheels of a car thereon when one end of the platform is depressed; substantially as specified. 75
8. In a device of the class described, an elevator-platform, a pivoted platform at one side thereof having a projection to engage beneath said elevator, means for restoring said platform to its initial position when the elevator-platform is out of engagement therewith, a pivoted retaining-dog carried by said pivoted platform and movable away from the wheels of a car thereon when one end of the platform is depressed, a caging-dog to engage the 85 wheels of a car upon said elevator-platform, and means for shifting said dogs out of engagement with said wheels when the elevator reaches its lowest position; substantially as specified. 90
9. In a device of the class described, an elevator-platform, a pivoted platform at one side thereof, a dash-pot having an apertured piston connected to the descending end of said pivoted platform, and a by-pass extending 95 around the piston in said dash-pot and provided with a check-valve; substantially as specified.
10. In a device of the class described, an elevator, a pivoted platform at one side thereof, 100 a projection from said platform to be engaged by said elevator in its downward movement, retaining-dogs pivotally mounted at the opposite side of said platform and having extended lever ends, a pivoted operating-lever 105 upon a fixed support, a link connecting one end of said lever with said platform, and toggle-levers extending from the opposite end of said lever to the lever ends of said dogs; substantially as specified. 110
11. In a device of the class described, an elevator-platform having tracks thereon, a pivoted caging-dog at one side of said tracks, a shaft disposed beneath said platform and provided with a crank-arm, a rod connecting the 115 lower end of said dog and crank-arm, a weighted arm carried by said shaft for normally throwing said dog toward said track and a movable support independent of the platform to temporarily engage said weighted arm; substantially as specified. 120
12. In a device of the class described, an elevator-platform having tracks thereon, a pivoted caging-dog at one side of said tracks, a shaft disposed beneath said platform and provided with a crank-arm, a rod connecting the 125 lower end of said dog and crank-arm, a weighted arm carried by said shaft for normally throwing said dog toward said track,

and means for shifting said weighted lever when the elevator is at its lowest position; substantially as specified.

13. In a device of the class described, an elevator-platform having tracks thereon, a pivoted caging-dog at one side of said tracks, a shaft disposed beneath said platform and provided with a crank-arm, a rod connecting the lower end of said dog and crank-arm, a weighted arm carried by said shaft for normally throwing said dog toward said track, means for shifting said weighted lever when the elevator is at its lowest position, and a lever for moving said supporting means to permit a return movement of the weighted lever after the elevator is at rest; substantially as specified.

14. In a device of the class described, an elevator-platform having tracks thereon, a pivoted caging-dog at one side of said tracks, a shaft disposed beneath said platform and provided with a crank-arm, a rod connecting the lower end of said dog and crank-arm, a weighted arm carried by said shaft for normally throwing said dog toward said track, means for shifting said weighted lever when the elevator is at its lowest position, a lever for moving said supporting means to permit a return movement of the weighted lever after the elevator is at rest, a projection from said moving lever adapted to be engaged by a car, and means for restoring said lever to its normal position; substantially as specified.

15. In a device of the class described, an elevator-platform, a pivoted dog mounted thereon, a lever for shifting said dog disposed beneath the platform, a sliding trip-block having its upper face adapted to engage and move said lever, a depressed seat to permit of said lever into a lowered position, a shifting lever projecting into the path of a car and pivoted at its lower end, and means for restoring said shifting lever; substantially as specified.

16. In a device of the class described, an elevator-platform provided with tracks, and a pivoted caging-dog adapted to move toward and from said tracks and provided at one end

with a laterally-deflected flange extending 5° vertically away from said tracks; substantially as specified.

17. In a device of the class described, an elevator-platform having a track thereon, pivoted caging-dogs at opposite sides of said track, a horizontally-disposed shaft supported beneath the platform and between the dogs, crank-arms extending from said shaft, rods connecting the lower end of said dogs with said cranks, and an operating-lever extended laterally from said shaft; substantially as specified.

18. In a device of the class described, an elevator-cage having a horizontally-disposed platform thereon, a receiving-platform at one side thereof, adapted to be inclined at an angle to the plane of the cage-platform; and a discharge-platform at the opposite side thereof in a lower plane than the receiving-platform and in the plane of the cage-platform when at its lowest position; substantially as specified.

19. In a device of the class described, an elevator-cage having a horizontally-disposed platform, a receiving-platform at one side thereof, a discharge-platform at the opposite side thereof in a parallel lower plane, and means for automatically inclining the receiving-platform at an angle to the elevator-cage platform when the latter is in the plane of the discharging-platform; substantially as specified.

20. In a device of the class described, an elevator-cage, a receiving-platform at one side thereof, a discharge-platform at the opposite side thereof in a parallel lower plane, means for automatically inclining the receiving-platform toward the elevator-cage when the latter is in the plane of the discharging-platform, and means for automatically releasing cars upon the receiving-platform and elevator-cage; substantially as specified.

In testimony whereof I affix my signature in presence of two witnesses.

WILLIAM TOWERS.
